INDUCTIVE HEATING COIL SHIELDING

Luther W. Gregory, Baltimore, and Stanley S. Schneider, Halethorpe, Md., assignors to Westinghouse Electric Corporation, East Pittsburgh, Pa., a corporation of Pennsylvania

Application November 5, 1942, Serial No. 464,672

12 Claims. (Cl. 219—13)

Our invention relates to high-frequency inductive heating-coils for operating at such a large power-input that the danger of corona, or other space-current discharges, is an important consideration in the design, by reason of the high electrostatic stress between the high-voltage portions of the coil and the work being heated. More particularly, our invention relates to a coil-construction including improved means for shielding the work against space-current discharges, while offering but slight hindrance to the axial magnetic lines of force within the work being heated.

Although our invention, in its broadest aspects, is not limited to any particular field of application, the most important present field of application for our invention is in connection with the tinplate-flowing apparatus which is described and claimed in an application of Glenn E. Stoltz and Robert M. Baker, Serial No. 464,040, filed October 31, 1942, and assigned to the Westinghouse Electric & Manufacturing Company. In this tinplate-flowing application of our invention, a miles-long strip of steel, or other magnetizable metal, is caused to run, at a very high rate of speed, through a tinning "line" or mill, in which various operations are successively performed on the strip, including electrolytically tinplating it on both sides, quickly heating it to a temperature of 452° F., or slightly thereafter, for the purpose of melting the tinplate and causing it to flow evenly and glossily over the surface of the steel to enhance its corrosion-resistant properties, as well as improving its appearance, subsequently quenching the strip, and performing various additional operations thereon, having nothing to do with the present invention, except that it is necessary to gauge the rate of heat-input into the strip to correspond to the large poundage of material which has to be heated per minute, preferably within as short a strip-length as is practically possible.

The most satisfactory method of heating such a fast-moving strip, and practically the only method of controllably introducing the necessary quantity of heat within an acceptably short length of the fast-moving strip, is the inductive heating method, in which the strip is passed axially through an inductive heating-coil which is supplied with a large amount of power from a high-capacity oscillator-tube generator-means. In a typical tinplate-flowing application of our invention, the inductive heating-coil receives many times as much energy as is used by the largest radio broadcasting station in the United States. With such large energy-input into the inductive

heating-coil, the coil-voltage becomes so high as to be one of the limiting or controlling features of the coil-design, and the danger of corona to the strip, or other work being heated, is an important phase of the high-voltage limitation.

The object of our present invention is to provide grounded electrostatic field-shielding means which is associated with the inductive heating-coil in a novel manner whereby various improved results are obtained, over and above previous known methods of induction-coil shielding.

Two exemplary forms of embodiment of our invention are illustrated in the accompanying drawing, wherein

15 Fig. 1 is a diagrammatic view of a tinplate-flowing application of our invention, including a longitudinal cross-sectional view through the induction-coil structure, looking edgewise on the strip being heated.

20 Fig. 2 is a transverse cross-sectional view illustrating the relation between the coil, the strip, the liner surrounding the strip within the coil, the airgap between the liner and the coil, and the grounded shielding coating painted on the liner.

25 Fig. 3 is a cross-sectional view of another form of embodiment of our invention, which is illustrated in connection with a wire-heating apparatus.

30 Fig. 4 is an elevational view of a portion of the liner on a reduced scale, showing a modified form of shielding-means, and

Fig. 5 is a vertical sectional view of the modification shown in Fig. 4.

In Figures 1 and 2, we show our invention as 35 being applied to the rapid inductive heating of a rapidly moving tinplated steel strip 4, which generally has a gauge of between 0.008 and 0.011 inch, with a width of the order of 28 to 36 inches, more or less, and which is moving, in the direction of its length, at a speed which may be of the order of a thousand feet per minute, more or less. This strip 4 passes axially downwardly through an inductive heating coil 5, comprising a plurality of

40 turns of a hollow conductor, wound in a single layer, and cooled by circulating water or other coolant, which may enter the coil at a grounded midpoint 6, and which may leave the coil at two insulated terminals 7 and 8. The coil-terminals are electrically connected, at 9 and 10, to a high-power oscillation-generator 12, which may have a high frequency in the range from 20 kilocycles to 500 kilocycles per second, or other frequency suitable for the gauge and material of the strip 4 or other elongated conducting member which is 45 to be heat-treated.

Disposed within the coil 5, is a solid insulating separating-means 18 having portions on opposite sides of the strip 4 or other work to be heated, said separating-means being preferably in the form of an insulating liner, closed at both edges of the strip, as shown at 14 in Fig. 2, so as to completely enclose the strip 4 being heated. This liner may be made of asbestos board, or a molded re-enforced insulating material having adequate heat-resistant properties and adequate mechanical strength for the particular application of the invention. The liner 18 has an opening 15 therethrough, through which the strip or elongated member 4 is threaded, and the entrance-end of the opening 15 may be provided with a rubber guiding-means 16 for reducing the probability of contact between the strip 4 and the inner surface of the liner 18.

The outer periphery of the liner 18 is preferably spaced, by an airgap 17, from the inner periphery of the coil 5, particularly when the work 4 to be heated is of magnetizable material, so that the heating-efficiency is less deleteriously affected by enlarging the coil 5 sufficiently to provide the airgap-space 17, or a space which is occupied by substantially nothing but a gaseous ambient medium, particularly in the portions of the space between the ungrounded or high-voltage portions or terminals of the coil and the work 4 being heated. This airgap 17 is advantageous, because air has a specific inductive capacity, or dielectric constant, of substantially unity, which is much lower than the dielectric constant of any available solid insulating material, so that most of the electrostatic voltage-drop, between the high-voltage ends of the coil and the work 4 being heated, which is usually grounded, takes place in the airgap 17, rather than in the solid insulation of the liner 18. The problem of corona is experienced only when the strip 4 swings out of its central position of alignment, and comes into contact, or near-contact, with the inner surface of the liner 18, and under these conditions, the airgap 17 between the liner and the coil is an effective means for reducing the electrostatic field-stress between the liner and the strip 4 or other work being heated.

In accordance with our present invention, we provide a means whereby the voltage of the coil can be pushed higher than can be provided for, in any practical design, by means of the airgap 17 alone. For the extremely high-power applications for which our invention is intended, we provide, therefore, a suitable grounded electrostatic field-shielding means, which is associated with the liner 18, for preventing corona between the strip 4 and the liner 18. Preferably this corona-preventing means is in the form of a grounded semi-conducting adherent coating 18, which is painted on a surface of the liner 18, preferably on the outer surface thereof, as shown in Figs. 1 and 2, this coating being suitably grounded at some point, as indicated at 19 in Fig. 1, wherein the grounding point is at an extended end of the liner 18, which extends axially beyond the length of the coil 5, into a region where the alternating magnetic field is relatively weak.

The grounded semi-conducting adherent coating 18 may be a coating of very finely divided graphite, suspended in water, and known as "aquadag," or it may be any other semi-conducting adherent coating, such as a compound of varnish, or other insulating binder, with a semi-conducting powdered material, such as wood-

charcoal or powdered titanium dioxide which has been partially reduced in a hydrogen furnace. The painted shielding-coating 18 necessarily has such a high resistivity or such a thinness, or both, that it is not materially heated by the alternating magnetic flux of the coil, which is another way of saying that it offers but slight hindrance to the axial magnetic lines of force which reach the strip 4 or other work being heated. The thickness of the semi-conducting coating 18 is necessarily greatly exaggerated, in Figs. 1 and 2, in order that it may be shown at all.

In operation, our grounded semi-conducting shield 18 holds down the voltage of the insulating liner 18 to a value which is sufficiently close to ground, at all points, so that no corona is experienced between the work 4 and the liner 18. By this means, it is possible to extend the power-input into the coil 5 to any desired voltage which is free of any consideration of corona or other space-current discharge playing upon the work 4. Of course, when this is done, the internal cross-sectional area embraced by the coil 5 must be enlarged, so that the airgap 17 will be of sufficient thickness to withstand arcing from the inner periphery of the coil 5 to the grounded shield 18, and sometimes it is necessary, also, to avoid excessive corona-discharges between the coil and the shield. It has been found, however, particularly where the work 4 is magnetizable, as is the case in tinplate-flowing apparatus, that the efficiency of heating is not very greatly reduced by enlargement of the inductive heating-coil 5, so that it is possible to rather extensively increase the radial length or thickness of the airgap 17 without very serious reduction in efficiency, when the paramount consideration is the introduction of as much heat as possible into as short a length of the strip 4 as possible.

The insulating liner 18 and the coil 5 must obviously both be suitably supported, in a manner which does not interfere with the airgap 17 between them. In Fig. 1, we have shown a form of support which is described and claimed in an application of Harold J. Frostick and Elvyn M. Sollie, Serial No. 464,042, filed October 31, 1942, assigned to the Westinghouse Electric & Manufacturing Company. The outer periphery of the coil 5 is embedded in a molded insulating material 21, which may be asphalt, or a casting resin, or other suitable insulating material. Both the coil-support 21 and the liner 18 extend axially beyond the ends of the coil 5, and the space between them is closed, at each end, by an annular insulating end-closure 22, which preferably makes a dust-tight compartment for completely enclosing the coil 5.

In Fig. 3, we show a form of embodiment of our invention in which we utilize two concentric insulating liners, the inner liner 18' being surrounded by an outer liner 23 of solid insulating material, which may either fit rather snugly within the coil 5', or the coil may actually be wound upon the outer liner 23 as a mandrel. The space between the two liners 18' and 23 is filled with a quantity of flowed material 18', which includes a substantially insulating binder, and a semi-conducting powdered material or other means which constitutes a semi-conducting shielding-means for controlling the electrostatic field, the shielding-means being grounded as indicated at 19'. In this manner, substantially the entire electrostatic stress is taken up by the outer liner 23, between the outer and inner peripheries thereof, so that there is practically no, or only

a relatively small, electrostatic stress in the inner liner 13', thus preventing corona from appearing on the work being heated. At the same time, the flowed material 18' substantially excludes air from the space between the liners 13' and 23, and thus eliminates corona, which is a gaseous-discharge phenomenon.

In the particular form of our invention which is shown in Fig. 3, we have illustrated the work being heated as being in the form of a rapidly moving wire 24, which may or may not be of a magnetizable metal.

While we have had good success heretofore with a semi-conducting shielding-coating 18 extending all the way around the periphery of the insulating liner 13-14, there may arise cases, particularly at the higher radio-frequencies or at high magnetizing forces, where the circumferential eddy-current voltage may be too high for satisfactory results with this type of circumferentially extending shield, making a complete eddy-current path around the periphery of the liner 13.

Accordingly, in Figs. 4 and 5, we have shown a modified form of shielding-coating 25 which is provided with axially extending unpainted-strips 25', except at the end, which is attached, at 25'', to the grounded connection 19. Since the mid-point of the inductive heating coil 5 is grounded, no shielding is needed opposite this point, and therefore two painted-on shields 25 may be utilized, one grounded at 19 and the other at 19', the grounding connections being at points beyond the respective ends of the coil 5, where the magnetic flux-density is weak, so that the eddy-current interruptions 25' are not needed.

In order to avoid corona across the axially extending bare-places 25' between the strips of the shield 25, the whole surface may be painted over with a semi-conducting coating 26, Figs. 4 and 5, which extends around the entire circumference, but has a sufficiently high resistivity so that eddy-current heating is not excessive. In this manner, the composite shield 25-26 has a relatively low axial resistivity, along the strips of the first coating 25, and a much higher circumferential resistivity, which is necessary or desirable in order to reduce the eddy-current heating of the shield. The two coatings 25 and 26 may be of the same or different coating-materials, and of the same or different thicknesses, so as to have the same or different linear resistivities.

While we have illustrated our invention in two preferable or illustrative forms of embodiment, we wish it to be understood that our invention, in its broadest aspects, is not limited to these precise forms, and we desire that the appended claims shall be accorded the broadest construction consistent with their language and the prior art.

We claim as our invention:

1. Apparatus adapted to heat an elongated work to be heated within a gaseous medium at approximately atmospheric pressure, said apparatus including, in combination, an induction heating coil comprising a plurality of turns of a cooled conductor wound in a single layer, means for supplying such a large high-frequency current to the coil that the danger of space-current discharges from the coil to the work due to a high electrostatic stress is an important consideration in the design, a solid insulating separating-means disposed within the coil with portions of said separating-means adapted to be on opposite sides of the work to be heated, means for supporting the

separating-means and the coil in such manner that most of the space between the separating-means and the high-voltage portions of the coil is substantially nothing but a gaseous ambient medium, said gaseous space being adequate to take most of the voltage-drop between the high-voltage portions of the coil and the work being heated, and grounded electrostatic field-shielding means in intimate contact with the separating-means for guarding the work being heated against space-current discharges while offering but slight hindrance to the axial magnetic lines of force within the work being heated.

2. Apparatus adapted to heat an elongated work to be heated within a gaseous medium at approximately atmospheric pressure, said apparatus including, in combination, an induction heating coil comprising a plurality of turns of a cooled conductor wound in a single layer, means for supplying such a large high-frequency current to the coil that the danger of space-current discharges from the coil to the work due to a high electrostatic stress is an important consideration in the design, a solid insulating separating-means disposed within the coil with portions of said separating-means adapted to be on opposite sides of the work to be heated, means for supporting the separating-means and the coil in such manner that most of the space between the separating-means and the high-voltage portions of the coil is substantially nothing but a gaseous ambient medium, said gaseous space being adequate to take most of the voltage-drop between the high-voltage portions of the coil and the work being heated, and a grounded semi-conducting adherent coating on a surface of the separating-means.

3. Apparatus adapted to heat an elongated work to be heated within a gaseous medium at approximately atmospheric pressure, said apparatus including, in combination, an induction heating coil comprising a plurality of turns of a cooled conductor wound in a single layer, means for supplying such a large high-frequency current to the coil that the danger of space-current discharges from the coil to the work due to a high electrostatic stress is an important consideration in the design, a solid insulating liner disposed within the coil and having an axially extending opening therein for accommodating the work to be heated, the outer periphery of the liner being spaced from the inner periphery of the coil and being separated from at least the high-voltage portions of the coil essentially by a gaseous ambient medium, and grounded electrostatic field-shielding means in intimate contact with the liner for guarding the work being heated against space-current discharges while offering but slight hindrance to the axial magnetic lines of force within the work being heated.

4. Apparatus adapted to heat an elongated work to be heated within a gaseous medium at approximately atmospheric pressure, said apparatus including, in combination, an induction heating coil comprising a plurality of turns of a cooled conductor wound in a single layer, means for supplying such a large high-frequency current to the coil that the danger of space-current discharges from the coil to the work due to a high electrostatic stress is an important consideration in the design, a solid insulating liner disposed within the coil and having an axially extending opening therein for accommodating the work to be heated, the outer periphery of the liner being spaced from the inner periphery of the coil and being sepa-

rated from at least the high-voltage portions of the coil essentially by a gaseous ambient medium, and a grounded semi-conducting adherent coating on a surface of the liner for guarding the work being heated against space-current discharges while offering but slight hindrance to the axial magnetic lines of force within the work being heated.

5. Inductive heating apparatus for heat-treating a continuously moving elongated member of magnetizable metal moving in the direction of its length, said apparatus comprising an induction heating coil comprising a plurality of turns of a cooled conductor wound in a single layer, means for supplying such a large high-frequency current to the coil that the danger of space-current discharges from the coil to the elongated member due to a high electrostatic stress is an important consideration in the design, a solid insulating separating-means disposed within the coil with portions of said separating-means adapted to be on opposite sides of the elongated member, means for supporting the separating-means and the coil in such manner that most of the space between the separating-means and the high-voltage portions of the coil is substantially nothing but a gaseous ambient medium, said gaseous space being adequate to take most of the voltage-drop between the high-voltage portions of the coil and the elongated member, and grounded electrostatic field-shielding means in intimate contact with the separating-means for guarding the elongated member against space-current discharges while offering but slight hindrance to the axial magnetic lines of force within the elongated member.

6. Inductive heating apparatus for heat-treating a continuously moving elongated member of magnetizable metal moving in the direction of its length, said apparatus comprising an induction heating coil comprising a plurality of turns of a cooled conductor wound in a single layer, means for supplying such a large high-frequency current to the coil that the danger of space-current discharges from the coil to the elongated member due to a high electrostatic stress is an important consideration in the design, a solid insulating separating-means disposed within the coil with portions of said separating-means adapted to be on opposite sides of the elongated member, means for supporting the separating-means and the coil in such manner that most of the space between the separating-means and the high-voltage portions of the coil is substantially nothing but a gaseous ambient medium, said gaseous space being adequate to take most of the voltage-drop between the high-voltage portions of the coil and the elongated member, and a grounded semi-conducting adherent coating on a surface of the separating-means.

7. Inductive heating apparatus for heat-treating a continuously moving elongated member of magnetizable metal moving in the direction of its length, said apparatus comprising an induction heating coil comprising a plurality of turns of a cooled conductor wound in a single layer, means for supplying such a large high-frequency current to the coil that the danger of space-current discharges from the coil to the elongated member due to a high electrostatic stress is an important consideration in the design, a solid insulating liner disposed within the coil and having an axially extending opening therein for accommodating the elongated member, the outer periphery of the

liner being spaced from the inner periphery of the coil and being separated from at least the high-voltage portions of the coil essentially by a gaseous ambient medium, and grounded electrostatic field-shielding means in intimate contact with the liner for guarding the elongated member against space-current discharges while offering but slight hindrance to the axial magnetic lines of force within the elongated member.

10 8. Inductive heating apparatus for heat-treating a continuously moving elongated member of magnetizable metal moving in the direction of its length, said apparatus comprising an induction heating coil comprising a plurality of turns of a cooled conductor wound in a single layer, means for supplying such a large high-frequency current to the coil that the danger of space-current discharges from the coil to the elongated member due to a high electrostatic stress is an important consideration in the design, a solid insulating liner disposed within the coil and having an axially extending opening therein for accommodating the elongated member, the outer periphery of the liner being spaced from the inner periphery of the coil and being separated from at least the high-voltage portions of the coil essentially by a gaseous ambient medium, and a grounded semi-conducting adherent coating on a surface of the liner.

15 9. Inductive heating apparatus for heat-treating a continuously moving elongated member of conducting material moving in the direction of its length, said apparatus comprising an induction heating coil comprising a plurality of turns of a cooled conductor wound in a single layer, means for supplying such a large high-frequency current to the coil that the danger of space-current discharges from the coil to the elongated member due to a high electrostatic stress is an important consideration in the design, a solid insulating liner disposed within the coil and having an axially extending opening therein for accommodating the elongated member, means for supporting said liner and said coil and means for providing therebetween a dielectric having a dielectric strength adequate to withstand substantially the entire voltage-drop between the coil and the elongated member, a quantity of flowed material in intimate contact with the outer periphery of said liner, between said liner and said dielectric, said flowed material including a substantially insulating binder and means for constituting a shielding-means for controlling the electrostatic field, and means for grounding the shielding-means without materially hindering the magnetic field, and means for grounding the shielding-means.

20 10. The invention as defined in claim 9, characterized by said shielding-means comprising a grounded semi-conducting adherent coating on a surface of the liner, said coating having a plurality of axially extending strips of coating, separated by unpainted strips, except at the grounded end of the coating, said grounded end of the coating being at a point axially beyond the end of the induction heating coil and hence partially out of its magnetic field.

25 11. The invention as defined in claim 9, characterized by said shielding-means comprising a grounded semi-conducting adherent coating on a surface of the liner, said coating having a plurality of axially extending strips of coating, separated by unpainted strips, except at the grounded end of the coating, said grounded end of the coating being at a point axially beyond the end of the induction heating coil and hence partially out of

its magnetic field, and another semi-conducting adherent coating making contact with the axial strips of the first-mentioned coating and extending continuously circumferentially around the periphery of the liner at said grounded end of the coating.

12. The invention as defined in claim 9, char-

acterized by said shielding-means having a relatively low axial resistivity and a much higher circumferential resistivity, being continuous circumferentially.
